TOWEL DISPENSING CABINET

Donald G. Cowlin, Glendale, Calif.

Application June 25, 1937, Serial No. 150,301

18 Claims.

(Cl. 312—37)

This invention relates to towel dispensing cabinets wherein a plurality of towels composed of a textile material are contained, and from which they may be individually withdrawn for use and returned into the cabinet successively.

The provision of towels for individual use in public or semi-public washrooms or lavatories requires that they be carried in a manner easily available for use; that they be protected from contamination and maintained in a sanitary condition until used; and further, that means be provided to insure their transfer and isolated assembly for facile removal in bulk for laundering.

It is a principal object of the present invention to provide apparatus whereby each of a plurality of clean towels contained in a sanitary compartment may be removed from the compartment for use without requiring either contact of the towels with any unclean surface or the tangible manipulation by the user of any mechanism other than the towel to be used itself.

Another object is to provide means for automatically bringing each towel into position for use from a storage of clean towels, the operation of which is dependent upon the return of previously used towels into the cabinet, thereby preventing theft or careless distribution of towels after their use.

Another object is to provide a plurality of towels, each having one of their ends secured to a towel belt carried in and movable through a cabinet, and being disposed with respect to each other whereby they will overly some of the towels of said plurality, and protrude a uniform distance from under those towels which overly them, respectively.

Another object is to provide a clean surface of paper, fabric or the like at the mouth of the cabinet, over which the towels may be withdrawn for use, adapted to be replaced automatically for each towel.

Another object is to provide a means for automatically wrapping used towels in the cabinet to prevent their contact with clean towels therein contained, or with parts of the machine with which clean towels may subsequently be brought into contact.

Other objects and salient features of my invention, such, for example, as ease of operation, simplicity of construction, assembly of parts, expeditious installation and removal of the towels as a group for laundering, and individually for use; durability, and efficient arrangement, will

be obvious to those of skill in the art to which my invention appertains from an examination of the following description read in the light of the accompanying drawings, in which:

5 Fig. 1 is a perspective view of the cabinet of my invention;

Fig. 2 is a sectional view of the cabinet illustrating in broken elevation the towel carrying assembly;

10 Fig. 3 is a side elevation of my invention with the end of the cabinet removed, illustrating the position of certain parts at rest;

Fig. 4 is a view similar to Fig. 3 taken at the opposite end of the device;

15 Fig. 5 is an enlarged sectional view through the towel-moving mechanism as normally positioned for withdrawal of a towel;

Fig. 6 is a view of the end of the towel-carrying drum as moved by the withdrawal of a towel from the position shown in Fig. 3, contrasting therewith the position of various parts at these two extremes of operative movement;

20 Fig. 7 is a broken front elevation of the supporting mechanism on the inside of the wall for the paper rollers;

Fig. 8 is a side elevation of the paper-roll supporting structure from within the cabinet;

25 Fig. 9 is an elevation of the inner surface of one side wall of the cabinet illustrating the means for the pivoted support of the towel roll and the means for limiting the downward swing of the roll after the user releases a withdrawn towel from the position shown in Fig. 6 to that depicted in Fig. 3;

30 Fig. 10 is a sectional view of the composite towel drum with the towel belt removed, illustrating partly the relative disposition of the various bearings and principal moving parts;

Fig. 11 is a sectional view of a belt having a 35 plurality of towels sewed thereto illustrating generally the means for securing the ends of the belt together;

Fig. 12 is a broken plan view of the towel belt shown in Fig. 11 depicting the towels as normally overlapping each other;

40 Figs. 13 and 14 illustrate perspectively two modifications of the attachment of the towels to the belt with respect to each other.

45 Referring to the drawings in detail, the numerals of which indicate similar parts throughout the several views, 15 designates a cabinet comprising side walls 16 and 17 and a top 18. The front of the cabinet comprises an upper portion 19 hinged to the top 18, and a lower portion 20 hinged to a bottom 21. The lower portion 20

is secured to the frame (not shown) of the cabinet as at 22 adjacent the lower edge of the upper portion. The lower end of the upper portion 19 is recessed to form a slot 24 in the front of the cabinet through which towels 25, carried by a belt 26, later referred to in detail, may be withdrawn for use and subsequently returned into the cabinet.

An open drum 27 comprising an arcuate wall 28 having its opposite ends closed by end spiders 29 and 30, respectively, is eccentrically pivoted in the cabinet by means of pins 31, secured to the end spiders. Pins 31 are rotatably mounted in angular journal blocks 32 removably carried in brackets 33 secured to the side walls 16 and 17 of the cabinet. Brackets 33 each consist of three retaining walls 34 parallel to the back, top and bottom of the cabinet, respectively, between which the blocks 32 are slid through the front open end of the bracket, and in which they are held against accidental displacement by pins 35 (Fig. 9).

Within and concentric with the wall 28 a cylinder 36 is disposed which is journaled in the end spiders 29 and 30 by pins 37 so as to rotate freely and provide an inside carrier for the towel belt 26, later described.

From the opposite edges of the arcuate wall 28 the drum end spiders 29 and 30 are correspondingly extended as at 38 for the support of the ends of a curved closure plate 39 which overhangs the opening in the drum between the edges of wall 28. The lower end of plate 39 is centrally recessed as at 40 for a purpose herein-after described.

A drive roller 41 is rotatably supported in bearings carried in the upper horizontally-aligned portions of the extensions 38 of the end spiders 29 and 30 by means of a shaft 42, its axis being parallel to that of cylinder 36 and in a plane below the upper edge of arcuate wall 28 and slightly outside of a circle passing through said wall. A second drive roller 43 parallel to the roller 41 is mounted on a shaft 44 journaled in the end spiders 29 and 30 adjacent the recess 40 in closure plate 39 and normally in vertical alignment with roller 41, i. e., when the recess 40 and slot 24 in the cabinet are nearest adjacent each other. Each drive roller 41 and 43 is roughened or covered with sandpaper 45 or the like to frictionally engage the fabric of towel belt 26. A semi-circular guide 46 is provided, having its opposite ends secured to the end spiders 29 and 30, and extends downwardly from the upper edge of closure plate 39, between said plate and roller 41 with which it is concentric. From the lower end of guide 46, a second guide 47 similarly supported by the end spiders, extends laterally, over roller 43, and a portion thereof is spaced from and concentric with roller 43, terminating slightly below the upper end of recess 40 in closure plate 39.

A plurality of towels 25 preferably of equal length, are provided, each having one of their ends sewed or otherwise secured on a belt 26 in any manner well known in the art which will permit the unattached edge of each towel when lying substantially flat on the belt to protrude slightly from under those towels overlying it. In Figs. 11, 13 and 14 three embodiments permitting this disposition of the towels, are illustrated. Referring to Fig. 11, a plurality of towels 25 of any uniform length desired for individual use are each secured at one end to the belt in spaced relation to each other as at 48. When lying flat on the belt their ends will be spaced

a distance substantially equal to the distance between their points of attachment 48 on the belt. In Fig. 13 the towels 49 are of double length and are secured to the belt 26 intermediate their ends, forming two reaches of each towel of unequal length. It will be apparent that when lying flat on the belt in a direction to the side of the longest reach, the edges of the respective reaches will maintain substantially the same spaced relationship as when hanging from the belt as shown in Fig. 13. In Fig. 14 a transverse middle portion 50 of each of a plurality of double length towels 49 is secured to the belt so that reaches of equal length will be spaced from each other and when lying flat on the belt their respective edges will also assume spaced relationship. Ends of the belt 26 are releasably fastened together by a zipper 51 (Figs. 11 and 12) or by other means well known in the art.

A towel belt 26 is installed on the carrier assembly (comprising wall 28, cylinder 36 and rollers 41 and 43) by passing the forward end 52 of the belt to the rear and under the drum 27, over arcuate wall 28 to and between the drive roller 41 and guide 46; rearwardly under the roller 41, over the top of cylinder 36, and forward to and over roller 43 for attachment to the opposite rearward end 53 of the belt 26 by means of zipper 51. As above described, the towels overlie each other and extend obliquely rearward from their point of attachment to the belt with respect to the forward end 52 thereof. The belt is moved, by means later referred to, in the direction just described to successively bring the free ends of each of the towels into alignment with slot 24.

A supporting bracket 54 for the end of a pair of rollers is secured to each side of the cabinet adjacent to and horizontally aligned with slot 24 in the front of the cabinet. Each bracket 54 comprises an upwardly directed U-shaped member 55 spaced from and secured to the walls 16 and 17 of the cabinet in any well known manner. Pin extensions 56 at opposite ends of and concentric with the roller 57 are journaled in the bottom of the U-shaped member 55 to rotatively support the roller horizontally slightly above the lower edge of slot 24. A roller 58 carrying a roll of paper 60 is supported on guide roller 57 and is provided at opposite ends with pin extensions 59 which are retained in the member 55 to hold the roller against lateral displacement. The free end of paper roll 60 is passed over the forward side of roller 57 (Fig. 5) and thence downwardly and rearwardly to the lower end of the cabinet where it passes over another roller 61 horizontally journaled in the lower side walls 16 and 17 of the cabinet. From the roller 61 the paper extends upwardly to the rearward end of the towel belt 26 to which it is secured.

It will be apparent that placement of the towel belt on the drive rollers 41 and 43 and the drum 27 in a position with the forward end of the belt under the drum, the free end of the first towel (the towel nearest adjacent the forward end 52 of the belt) will have been moved from under the guide 47 and will be below the upper end of the recess 40 where it may be gripped by a prospective user. The edges of the towel drawn from under the guide 47 by the movement of the belt will then be releasably retained on the roller 43 by the lower side edges of the plate 39 at opposite sides of the recess 40. By gripping the towel edge in the recess 40, the user may draw the towel from under the lower sides

of the plate 39, over the paper on roller 58, and through slot 24, causing the entire drum and towel belt 26 to swing counterclockwise on pins 31 to a position with the point of attachment of the withdrawn towel to the belt, adjacent to the roller 58 and slot 24 (Fig. 6), which enables use of the entire length of the towel by the user. Upon release of the towel by the user, the drum, due to its eccentric point of pivot and weight of the drive rollers 41 and 43 and associated mechanism on the forward side of the drum, will swing back to its original position, drawing the released, soiled towel through the slot 24 and into the cabinet. Used towels will hang freely from the belt as is indicated in the drawings at 62 (Fig. 5). As the forward end of the belt is moved over the wall 28 toward roller 41 the used towels 62 will overly each other in the same manner as the fresh towels, and will be separated from the fresh towels, secured to the rearward end of the belt, by a paper covering from roll 60, as will be hereinafter more in detail described.

During withdrawal of the first towel from the slot 24 for use as just above described, the belt is moved slightly in the direction above indicated to cause the movement of the unattached end of the second towel from under guide 47 for engagement and withdrawal by a user.

To effect this operation, a fixed bar 63 is rigidly connected to one of journal blocks 32, and extends obliquely rearward and downward therefrom. A curved connecting arm 64 is pivoted to the lower end of bar 63 having its upwardly curved opposite end pivoted to the middle of a normally vertical rocker arm 65, which in turn is pivoted at opposite ends to cranks 66 and 67. Cranks 66 and 67 are pivotally connected to shafts 42 and 44 of the rollers 41 and 43, respectively. On the end of shaft 42 and 44, adjacent the pivotal attachment of respective cranks, ratchet wheels 68 and 69 are non-rotatably mounted. A spring-pressed pawl 10 is pivoted to each crank 66 and 67 to engage and cause rotation in a clockwise direction of the ratchet wheels 68 and 69 and their respective rollers upon their actuation in a manner about to be described.

As the drum is swung counterclockwise in response to the tension applied to the belt 26 by a user in withdrawing a towel from the cabinet, the connecting arm 64, being pivoted at one end to fixed arm 63, draws the rocker arm 65 toward the axis of the drum 27 at 31 so as to arcuately swing the crank arms 66 and 67 on the shafts 42 and 44, respectively. The ratchet wheels 68 and 69 and rollers 41 and 43 will be, coincidentally, partially rotated in the same direction by pawls 10 which engage behind teeth on the respective ratchet wheels.

It will be observed that as the free ends of the towels are moved adjacent the slot 24 in response to successive operations of the machine, the plate 39 and guide 47 cooperate in maintaining the ends of the towels overlying one another and in position for facile engagement by the fingers of the prospective user.

On the opposite ends of the drive rollers 41 and 43, exterior of the drum, their respective shafts are provided with rigidly mounted pinions 71. Between the pinions 71, a spur gear 72 is journaled on the end spider 30, which gear 72 engages with the pinions 71. A squared shank 73 integrally connected with the spur gear 72 extends through the adjacent side wall of the cab-

inet. A handle 74 shown in dotted lines in Fig. 2 may be thus employed to facilitate installation and removal of the towel belt 26.

The necessary tendency of the belt carrier assembly to return to a position in which the free end of the next-to-be-used towel will be adjacent slot 24 to permit its withdrawal therethrough, requires that means be provided to limit this return motion. To this end a guide rail 75 is secured horizontally to the side wall 17 of the cabinet so as to project laterally therefrom. At the forward end of the rail 75 a vertical lug 76 is provided through which a screw 77 is threaded having pivotally secured to its threaded end an abutment 78, against which a stop 79, secured to the adjacent end spider 30, will abut when the towel assembly is at rest. Exact adjustment of the limit of the clockwise motion of the towel carrier assembly may be effected by rotation of the screw 77 in a manner well known in the art. At the inner end of the rail 75 opposite to lug 76, a fixed abutment 80 is secured toward which a stop 81, secured to the end spider 30 a distance, in a clockwise direction from the abutment, substantially equal to the length of the individual towels employed, will be moved as the drum 27 is swung counterclockwise in response to the withdrawal of a towel. Thus when the end of the towel which is attached to the belt reaches slot 24 upon withdrawal by a user, stop 81 will contact abutment 80, preventing an excessive counterclockwise movement of the drum which might result in jamming of the towels against the wall of the cabinet.

The paper from roller 58 having its end secured to the rearward end of belt 26, will be unreeled as the belt is moved in response to the urge imparted thereto resulting from withdrawal of the towels, due to the outer end of the paper being drawn with the end of the belt toward recess 40. When all towels have been used, the forward end of the belt will again be positioned under the drum and the paper from roller 58 will have formed a covering over all towels which will at this period of operation extend over the lower drive roller 43 (preventing withdrawal of used towels from the cabinet) around the cylinder 36, under and over the used towels on drive roller 41 over the arcuate wall and thence downwardly under roller 61 to paper carrying roller 58. It will accordingly be seen that the paper performs the three-fold function of providing a clean paper surface for each towel at the slot 24 over which the towels are withdrawn; separating the used towels from the unused towels by forming a paper sheath over them as the belt moves along its course through the carrier, and returns to the lower roller 43 and slot 24 so that the used towels will be covered by the sheath to prevent withdrawal and repeated use; and further, prevents contamination of the parts of the machine by matter deposited on the towels at the time of their use which would in turn contaminate clean towels placed in the machine with the installation of a new belt.

While I have shown but one embodiment of my invention, it will be understood that numerous changes may be made in size, shape, proportion and number of the parts; the lower paper roller may be eliminated; and towels of any length may be employed with a corresponding variance in the swing of the carrier assembly upon withdrawal of a towel—all without departing from the spirit of my invention as defined in the appended claims.

What I claim and desire to secure by Letters Patent is:

1. In a device of the character described; a cabinet having a slot therein, a drum journaled horizontally within said cabinet adjacent said slot, having an opening therein parallel to the longitudinal axis of said drum, a drive roller carried by said drum adjacent said opening therein; a cylinder journaled within said drum, an endless towel belt extending over said drum and drive roller and between said drum and cylinder, and a plurality of towels carried on said belt.

2. In a device of the character described, a cabinet having a slot therein, a towel carrier comprising a drum having an opening therein parallel to the longitudinal axis of said drum, a cylinder journaled in said drum, means connected to said drum offset with respect to the longitudinal axis of the drum to journal said drum within said cabinet, a towel belt overlying the walls of said drum and the portion of said cylinder covered by the wall of said drum, a plurality of towels having one of their ends secured to said towel belt and the other end unattached, and means to move said towel belt over said drum and cylinder and adjacent said slot in said cabinet to bring the unattached end of each of said towels successively adjacent to and into alignment with said slot in said cabinet.

3. In a device of the character described; a cabinet having a slot therein, a drum member carried by and within said cabinet adjacent said slot, an endless towel belt carried on said member, a plurality of towels each having one of their ends secured to said towel belt, means to move said towel belt on said member adjacent said slot, and means to hold the towels in a position partially overlying one another as said towels are moved adjacent said slot.

4. In a device of the character described; a cabinet having a slot therein, a towel belt, a pair of towels each having one of their edges secured to portions of said towel belt spaced from each other a distance less than the length of said towels, means to normally maintain a portion of each of said towels substantially parallel to said belt, a drum journaled in said cabinet to carry said belt, means to move said belt over said drum to bring the unattached end of one of said towels adjacent said slot for withdrawal and use; said drum being movable by withdrawal of a towel to bring the attached end of the withdrawn towel adjacent said slot, and means to move said drum and belt to a position where the unattached edge of another of said towels is adjacent said slot.

5. In a device of the character described, a cabinet having a slot therein, a towel belt, a plurality of towels, each having one of their ends secured to said belt, means within said cabinet to carry said towel belt and towels, means to move said belt to positions with respect to the slot in said cabinet to successively bring each of said towels in a position for withdrawal from the cabinet, said last-mentioned means being intermittently actuated by successive withdrawal of the towel, means to move said belt to cause return of said towel into said cabinet after withdrawal; a roller, a sheet reeled upon said roller, the outer end of said sheet being secured to said towel belt, said sheet being unreeled by movement of said towel belt to cover said towels after their return into the cabinet.

6. In a device of the character described; a cabinet having a slot therein, a drum having an

opening therein parallel to its longitudinal axis, means to journal said drum in said cabinet substantially parallel with and adjacent to said slot in said cabinet, a cylinder journaled within said drum, drive rollers journaled respectively in the ends of said drum adjacent each edge of the peripheral wall of said drum forming said opening therein; an endless towel belt, a plurality of towels, each having one of its ends secured to said towel belt whereby each of said towels will overlie other of said towels and protrude from under those which overlie it respectively, said towel belt being disposed on said drum over said rollers and over the portion of said cylinder enclosed by the peripheral wall of said drum, retaining means to hold the towels on said belt which are nearest adjacent said slot in position substantially flat against said belt and substantially parallel with respect to each other, drive means to move said drive rollers to cause movement of said belt in the direction opposite to that in which said towels are inclined with respect to their point of attachment to said belt, and cause the successive withdrawal of the free edges of said towels from under said retaining means, said drum being movable in a direction opposite to the movement of the outer portions of said towel belt by said drive means to successively bring the respective points of attachment of each of said towels adjacent said slot in said cabinet, means to cause return movement of said drum and belt from the last-mentioned position, said last-mentioned movement causing the return of a used towel into the cabinet through the slot therein and further, causing by cooperation with said drive means to successively bring the unattached end of each towel into alignment with said slot in the cabinet, a roller journaled in said cabinet, a sheet carried on said roller having its outer end secured to said belt to separate used towels from unused towels.

7. In a device of the character described; a cabinet having a slot therein, a towel belt, a plurality of towels each having one of its ends secured to said belt, means to normally hold each of said towels in a position overlying other of said towels and protruding from under those which overlie it respectively, the opposite end of each of said towels being unattached, a carrier for said belt within said cabinet to successively support the unattached end of each of said towels adjacent said slot for withdrawal from said cabinet and use, means to move said belt with respect to said carrier to bring successively the free end of each of said towels to a position on said adjacent carrier for support thereby at said slot, said last-named means operating to move said belt to positions with the points of attachment to the belt of respective towels when partially withdrawn for use adjacent the slot.

8. In a device of the character described, a cabinet, a towel belt in said cabinet, carrier means to support said towel belt in said cabinet, a plurality of towels each having one of their ends secured to said belt, the other end of each of said towels being unattached, and means to hold said towels in positions whereby each of said towels will overlie other of said towels and protrude from under those towels which overlie it respectively, and means to move said belt to successively bring the point of attachment of each towel to the belt and the protruding portion of each towel adjacent the slot, said carrier being shiftable in said cabinet to reverse the di-

rection of movement of said towel belt adjacent said slot.

9. In a device of the character described, a cabinet having a slot therein, a belt, a plurality of towels each having one of their ends secured to said belt, a carrier for said belt including means to move the same adjacent said slot and successively move the unattached ends of said towels adjacent said slot, and a guide stationary relative to said last-named carried to successively engage said unattached ends of towels adjacent said slot to hold the towels in extended positions on said belt respectively during engagement therewith.

10. In a device of the character described, a cabinet having a slot therein, a belt, a carrier for said belt movably mounted in said cabinet, a towel having one portion thereof attached to said belt, means connected to said carrier to normally hold said towel in extended position on and substantially parallel to said belt, and means to move said belt to successively bring said attached portion of said towel and an unattached end of said towel adjacent said slot.

11. In a device of the character described, a cabinet, a towel carrier pivoted in said cabinet, a belt supported on said carrier, a plurality of towels each having one of their ends attached to said belt, drive means to move said belt on said carrier, and means actuated by movement of said carrier relative to said cabinet to actuate said drive means.

12. In a towel dispensing apparatus, a cabinet having a slot therein, a belt-carrier mechanism for movably supporting said belt adjacent said slot, a roller mounted in said cabinet parallel to said slot, a sheet reeled on said roller having one end thereof connected to said roller and its opposite end connected to said belt whereby movement of said belt relative to said carrier mechanism unreels said sheet so as to cover towels on said belt within said cabinet.

13. In a device of the character described, a cabinet having a slot therein, a towel, means connected to one end of said towel to move the unattached end of said towel adjacent said slot for manual withdrawal of said towel through said slot, a roller mounted in said cabinet parallel and adjacent said slot, a sheet reeled on said roller with which the towel contacts upon withdrawal of the towel through said slot, means to unreel said sheet, and means to synchronize the operation of said first-named and said last-named means.

14. In a device of the character described, a cabinet having a slot therein, an endless towel belt, a plurality of towels attached to said belt, means to move said towel belt and towels adja-

cent said slot, and means connected to said belt for movement therewith to sheath said towels successively upon being moved with the portions of said towel belt to which they are attached, respectively, from adjacent said slot.

15. In a device of the character described, a cabinet having a slot therein, a towel carrier journalled in said cabinet adjacent said slot comprising a drum having a cylinder within said 10 drum and an endless towel belt extending over a portion of said drum into said drum and between said drum and cylinder, and a plurality of towels carried on said drum.

16. In a device of the character described, a cabinet having a slot therein, a towel belt, a towel having one of its ends secured to said towel belt and having its other end unattached, means to successively move the portion of said belt to which said towel is attached and subsequently the unattached end of said towel, respectively, adjacent said slot, and means actuated by tension applied to said towel to return the portion of said belt to which the towel is attached adjacent said slot.

17. In a device of the character described, a cabinet having a slot therein, a towel belt, a plurality of towels each having one of their ends secured to said towel belt, a carrier for said belt within said cabinet, means to move said belt over said carrier to bring the unattached edges of said towels adjacent to said slot, said carrier being actuated by withdrawal of a towel from said slot for use to move said belt adjacent said slot in a direction opposite to the movement of the belt by said means, a roller journalled in said cabinet adjacent said slot over which said towels are moved upon withdrawal, a sheet reeled upon said roller, and means actuated by said first-named means to unreel said sheet as said belt is moved relative to said carrier.

18. In a device of the character described, a cabinet having a slot therein, an endless towel belt, a pair of towels each having one of its ends secured to said towel belt and its opposite end unattached, carrier means to support said belt and said towels with the unattached edge of one of said towels adjacent said slot, drive means associated and cooperating with said carrier means to displace the last-named towel from adjacent said slot, said belt being movable by said drive means and said carrier means to bring the unattached edge of the other of said towels adjacent said slot and to move the unattached edge of said first-named towel past said slot, and a non-absorbent sheet operatively connected to said belt to overly said first-named towel upon its movement past said slot.

DONALD G. COWLIN.
